UNITED STATES PATENT OFFICE

GEORGE W. BUNGAY, OF PLAINFIELD, NEW JERSEY, ASSIGNOR TO HOUSEHOLD FIELD CORPORATION, OF NEW YORK, N. Y., A CORPORATION OF NEW YORK

DESIGN FOR A JUICE EXTRACTOR

Application filed December 31, 1931. Serial No. 42,338. Term of patent 14 years.

To all whom it may concern:

Be it known that I, GEORGE W. BUNGAY, a citizen of the United States of America, residing at Plainfield, county of Union, and State of New Jersey, have invented a new, original, and ornamental Design for a Juice Extractor, of which the following is a specification, reference being had to the accompanying drawings, forming part thereof.

I claim:

The ornamental design for a juice-extractor as shown.

In testimony whereof I have affixed my signature to this specification.

GEORGE W. BUNGAY.
